UNITED STATES PATENT OFFICE.

ABRAHAM SCHUMACHER, OF WASHINGTON, DISTRICT OF COLUMBIA.

BLANKET STRETCHER.

Application filed March 21, 1923. Serial No. 626,679.

To all whom it may concern:

Be it known that I, ABRAHAM SCHUMACHER, a citizen of the United States, residing at Washington, in the District of Columbia, have invented certain new and useful Improvements in Blanket Stretchers, of which the following is a specification.

In carrying out the present invention, it is my purpose to provide a stretcher that is primarily, although not specifically adapted for the stretching of blankets, the device being characterized by the fact that it may be advantageously employed for stretching blankets or other articles of varying sizes.

15 A further purpose of this invention is the provision of such a blanket stretcher that embraces the desired features of simplicity, durability, and efficiency, the device comprising relatively few parts, and these correlated in such a manner as to reduce the liability of derangement to a minimum.

The nature and advantages of the invention will be better understood when the following detailed description is read in connection with the accompanying drawings, the invention residing in the construction, combination, and arrangement of parts as claimed.

25 In the drawings forming part of this application, like numerals of reference indicate similar parts in the several views, and wherein:

30 Figure 1 is a front elevation of my improved blanket stretcher.

35 Figures 2 and 3 are longitudinal cross sectional views, upon the lines 2-2 and 3-3, respectively, of Figure 1.

40 Figure 4 is an enlarged fragmentary vertical cross section of one side of the stretcher.

45 Figure 5 is a similar view of the opposite side of the device.

Figure 6 is a detail cross section upon the line 6-6 of Figure 1.

50 Figure 7 is a cross section of a portion of the device.

Figure 8 is a detail cross section of one of the elements comprised in the invention, and

55 Figure 9 is a perspective of a specific form of bolt member, also comprised in my invention.

Referring to the drawings in detail, my device comprises a frame designated generally by the numeral 5. This frame comprises end bars 6 and 7, an upper connecting

bar 8, and a lower connecting bar 9, each of these bars are of U channel iron construction, it being well to note that the end bar 7 has its outer edge rounded, as more clearly shown in the sectional view, Figure 3.

Secured to the lower ends of the end bars 6 and 7, and extending outwardly from each side thereof are supporting legs 10, the same carrying rollers 11, for facilitating the movement of the stretcher from place to place. Upon the upper side of the top cross bar 8 and at opposite edges are longitudinally extending guide bars for purposes hereinafter described, these guide bars consisting of the well known L irons. Within 70 each of the end bars 6 and 7 is a pair of spaced inwardly extending arms 13, the outer ends thereof being formed with collars 14. Between each pair of arms 13, and freely rotatable within the said collars 14 75 are rods 15, each of the same being formed with spiral grooves 16.

Journaled at one end within a bearing 17, formed upon the lowermost arm 13 within the end bar 6 and at its opposite end 80 within a bearing 18 formed upon an arm 19, within the said end bar and at a point distant from the arm 13 is a shaft 20. The last mentioned arm 19 has one end bent upwardly and is provided with a bearing 21, 85 and journaled at one end within this bearing is a stub shaft 22, this shaft extending outwardly of the frame bar 6, and being provided with an operating handle 23. Keyed upon the said stub shaft 22 is a 90 bevelled gear 24, in mesh with a bevelled gear 25, upon the adjacent end of said shaft 20.

95 Journaled within bearing brackets 26 within the lower frame bar 9 is a shaft 27, one end of the same having keyed thereto a bevelled gear 28, in intermesh with a bevelled gear 29 upon the lower end of said shaft 20. Adjacent the opposite ends of the shaft 27 and keyed thereon are other bevelled gears 30, each of which intermesh with a bevelled gear 31 upon the lower ends of the before mentioned spirally grooved rods 15.

100 Extending lengthwise of the frame 5 is a U bar 32, the opposite ends of the web portion thereof being channeled or cut away at 33. Within these channeled ends of the said bar 32 are blocks 35, through which extend spirally grooved rods 15, the ends of these 110

blocks being channeled as at 36, within which are positioned the side portions of the **U** bar 32. Each of these blocks 35 are provided with a screw threaded opening in communication with the central bore thereof, and within these openings are set screws 37, Figure 9. The front ends of these set screws are formed with projecting lugs 38, which engage within the spiral groove of each of the rods 15, whereby when these rods are rotated in opposite directions through the instrumentality of the operating handle 23, the said bar 32 is moved upwardly and downwardly within the frame 5 for purposes hereinafter described. Upon the opposite sides of the frame 5 are flat-like bars 39, and secured to the opposite ends of these bars are roller carrying plates 40, each of the said plates carrying a pair of grooved rollers 41, it being noted from a consideration of Figure 6 that the upper rollers are movable upon the said guide bars 12 of the upper frame bar 8, while the rollers upon the lower ends of said flat-like bars 39 are movable upon similar guide bars 12', upon the bottom side of said lower frame bar 9. Each of the said roller carrying plates 40 is formed with a screw threaded opening, within which is a screw threaded bolt 41, formed with a wing nut 42, and adapted for engagement with the adjacent guide bar 12 or 12' for effectively locking the said flat-like bars 9 against movement in a longitudinal direction.

35 Upon opposite sides of the top frame bar 8, and the said movable **U** bar 32, and surrounding the end frame bar 7 are metal strips 43, Figure 7, it being of course obvious that these said metal strips are each of a single length of material. Upon the outer faces of these metal strips are coverings of heavy fabric 44, the same being retained upon the said strips 43 by L-shaped metal strips 45 riveted or otherwise secured to the strips 43 as at 46. Carried by these fabric coverings 44 and projecting outwardly therefrom are the usual needle points 47, to which are secured the edges of the blankets or other articles to be stretched.

50 Upon the front faces of the said flat-like bars 39 are similar canvas strips, which also carry needle points 48, these canvas strips being secured to the flat-like bars through the medium of similar fastening strips 49.

55 In view of the above description, it is believed by me that the advantages and operation of a device of this character will be readily appreciated by those skilled in the art, and although I have herein shown and described the preferred embodiment of my invention, it is nevertheless to be understood that minor changes may be made therein, without departing from the spirit and scope of the invention, as claimed.

65 Having thus described my invention, what

I claim as new, and desire to secure by Letters Patent is:—

1. A curtain stretcher including a rectangular portable frame composed of rigidly connected top, bottom and end members, said end and bottom frame members being of channel form with inwardly extending flanges, a horizontal cross bar movable vertically between said end frame members, strips extending around one of the end frame

members and respectively secured on both sides of the top frame member and the horizontal cross bar, said strips having fabric engaging means from end to end thereof, and means including intergeared shafts carried by and mounted within the end and bottom frame members and operatively connected to the ends of the horizontal cross bar for raising and lowering the latter.

2. A curtain stretcher including a rectangular portable frame composed of rigidly connected top, bottom and end members, said end and bottom frame members being of channel form with inwardly extending flanges, a horizontal cross bar movable vertically between said end frame members, strips extending around one of the end frame members and respectively secured on both sides of the top frame member and the horizontal cross bar, said strips having fabric engaging means from end to end thereof,

and means including intergeared shafts carried by and mounted within the end and bottom frame members and operatively connected to the ends of the horizontal cross bar for raising and lowering the latter, pairs of spaced parallel guide bars fixed on the upper wall of the top frame member and on the bottom wall of the bottom frame member, a pair of opposed vertical cross bars disposed outwardly of the opposite sides of the top and bottom frame members and the horizontal cross bar and provided with fabric engaging means, grooved rollers on the ends of said vertical cross bars and riding on the outer edges of said guide bars, and means carried by the ends of the vertical cross bars and engageable with said guide bars to releasably hold the vertical cross bars against movement.

3. A curtain stretcher including a rectangular portable frame composed of rigidly connected top, bottom and end members, said end and bottom frame members being of channel form with inwardly extending flanges, a horizontal cross bar movable vertically between said end frame members, strips extending around one of the end frame members and respectively secured on both sides of the top frame member and the horizontal cross bar, said strips having fabric engaging means from end to end thereof, and means including intergeared shafts carried by and mounted within the end and bottom frame members and operatively connect-

ed to the ends of the horizontal cross bar for raising and lowering the latter, said last named means further embodying nut members carried by the ends of the horizontal 5 cross bar and vertical spirally grooved shafts operatively geared to the one of said inter-geared shafts which is disposed within the bottom frame member, said spirally grooved shafts extending through said nut members 10 and mounted on the side frame members inwardly of the latter.

4. A curtain stretcher including a rectangular portable frame composed of rigidly connected top, bottom and end members, 15 said end and bottom frame members being of channel form with inwardly extending flanges, a horizontal cross bar movable vertically between said end frame members, strips extending around one of the end frame 20 members and respectively secured on both sides of the top frame member and the horizontal bar, said strips having fabric engaging means from end to end thereof, and

means including intergeared shafts carried by and mounted within the end and bottom frame members and operatively connected to the ends of the horizontal cross bar for raising and lowering the latter, said last named means further embodying nut members carried by the ends of the horizontal 25 cross bar and vertical spirally grooved shafts operatively geared to the one of said inter-geared shafts which is disposed within the bottom frame member, said spirally grooved shafts, and extending through said nut mem- 30 bers and mounted on the side frame mem- bers inwardly of the latter, the ends of the web of the horizontal cross bar being cut away to leave the ends of the flanges thereof 35 projecting, and said nut members having channeled ends in which said projecting flange ends of the horizontal cross-bar are 40 engaged.

In testimony whereof I affix my signature.

A. SCHUMACHER.
